UNITED STATES PATENT OFFICE.

ERNEST D. ANDERSON, OF NEW YORK, N. Y., ASSIGNOR TO E. D. ANDERSON, INC., OF NEW YORK, N. Y., A CORPORATION OF NEW YORK.

LABELING-MACHINE.

1,318,715.

Specification of Letters Patent. Patented Oct. 14, 1919.

Application filed December 29, 1917. Serial No. 209,483.

To all whom it may concern:

Be it known that I, ERNEST D. ANDERSON, a citizen of the United States, and resident of New York city, borough of Manhattan, in the county of New York and State of New York, have invented certain new and useful Improvements in Labeling-Machines, of which the following is a specification.

The object of my invention is to provide means to automatically apply labels upon packages with adhesive material between the same to cause adherence of the labels to the packages.

In carrying out my invention I provide means to supply labels, means to feed packages, means to apply labels successively to the packages, and means to apply adhesive material between the labels and the packages before the labels are applied upon the packages, whereby as the packages are advanced successively the labels will be selected and applied to the successive packages.

My invention comprises novel details of improvement and combinations of parts that will be more fully hereinafter set forth and then pointed out in the claims.

Reference is to be had to the accompanying drawings forming part hereof, wherein, Figure 1 is a plan view of a machine embodying my invention; Fig. 2 is a side elevation of the machine looking in the direction of the arrow in Fig. 1; Fig. 3 is a cross section substantially on the line 3, 3, in Fig. 2, looking in the direction of the arrow; Fig. 4 is a cross section substantially on the line 4, 4, in Fig. 2, illustrating means for operating a label-applying presser; Fig. 5 is an enlarged sectional detail plan view illustrating the label supplying magazine and the label feeder; Fig. 6 is a longitudinal section substantially on the line 6, 6, in Fig. 5, looking in the direction of the arrow; Fig. 7 is an enlarged detail view illustrating a portion of the label feeder and a roller coactive therewith; Fig. 8 is an enlarged fragmentary sectional view through a portion of the label feeder; Fig. 9 is an enlarged detail cross section substantially on the line 9, 9, in Fig. 5, looking in the direction of the arrow; Fig. 10 is a fragmentary plan view, partly in section, of a portion of the label supply magazine and the label feeder; Fig. 11 is an enlarged fragmentary perspective view illustrating part of the label magazine and pusher for the labels; Fig. 12 is a detail plan view illustrating means for supplying adhesive for the labels; Fig. 13 is an end view of Fig. 12; Fig. 14 is a cross sectional view through the receptacle for the adhesive material, the section being taken substantially on the line 14, 14, in Fig. 15; looking in the direction of the arrow; Fig. 15 is a longitudinal section substantially on the line 15, 15, in Fig. 14; Fig. 16 is a side view of Fig. 13, illustrating the adhesive applying devices in a position elevated above a package; Fig. 17 is a detail view of part of Fig. 16, illustrating the adhesive applying devices co-operating with the package; Fig. 18 is a fragmentary perspective view illustrating a label supported in position to be applied upon a package, and Fig. 19 is a perspective view illustrating a package labeled in accordance with my improvements.

Similar numerals of reference indicate corresponding parts in the several views. The main frame of the machine, which may be of any suitable construction, is indicated at 1, and 2 indicates packages to which labels 3 are to be applied. The packages to be labeled may be supplied and fed to the labeling devices in any suitable manner, as by hand or from any suitable machine from which the packages are produced. I have illustrated a conveyer 4 to support the packages and which may comprise an endless belt carried upon guiding rolls 5, 6, whose shafts 7, 8, are shown journaled upon spaced supports 9, 10, on the main frame. The conveyer 4 is shown provided with battens 4^a spaced apart to receive the packages 2 to retain the latter in proper position for propulsion with the conveyer. At 4^b are indicated spaced guiding rails above the conveyer between which the packages 2 travel and are thereby guided and retained in proper position to receive the labels. Any suitable means may be provided for operating the conveyer. When my improved machine is utilized in conjunction with a machine for packaging goods the latter may be geared to one of the shafts 7 or 8, or to another shaft of the machine, for operating the conveyer 4 in timed relation to the delivery from the packaging machine of the packages to said conveyer. In the example illus-

trated I have shown a main drive shaft 11 which is journaled in bearings upon uprights 12 on the main frame, which shaft is provided with a sprocket wheel 13 receiving a chain 14 that passes over a sprocket 15 secured on a shaft 16 that is journaled in suitable bearings upon the main frame. Shaft 16 is shown provided with an arm 17 of a Geneva movement having a projection 18 or roller 18 adapted to coöperate with the slotted member 19 of the Geneva movement, which member 19 is carried by a shaft 20 journaled in a suitable bearing 21 on the main frame. Shaft 20 is shown provided 15 with a bevel gear 22 in mesh with a corresponding gear 23 secured upon shaft 7, the arrangement being such that during rotation of shaft 11 the roller 18 will be rotated intermittently through the action of the Geneva movement for correspondingly operating the conveyer step by step. Shaft 11 may be provided with a wheel 24 which may be driven from a suitable wheel upon the machine referred to for packaging the goods 20 and delivering the packages to conveyer 4. Any suitable clutch mechanism at 25 may be provided for starting and stopping the operation of shaft 11. When my improved machine is not operated in conjunction with 25 or in timed relation to the operation of a packaging machine the wheel 24 may be driven in any desired manner and the packages may be manually fed to conveyer 4.

At 26 is a supply magazine or chute for 30 the labels 3, which magazine is shown supported upon the uprights 12 by means of a brace 27 (Fig. 6) at a level higher than conveyer 4. Labels 3 are shown supported on edge within magazine 26, and to induce 35 the forward movement of a quantity of labels through the magazine, I provide a slide 28, shown having a base 28^a slidable upon the bottom of the magazine and provided with a post 29 from which extends a 40 rod 30, shown guided in the rear wall 31 of the magazine. A spring 32 coiled around said rod and bearing against said wall and against post 29 tends to induce forward movement of the slide. Magazine 26 has 45 spaced side walls 33 between which the stack of labels and the slide travel. At 34 is a label feeder, shown provided with pins or projections 35 projecting from the periphery thereof to engage the labels, which 50 feeder is shown secured upon shaft 11 for rotation thereby. The pins 35 extend far enough from the feeder to engage labels as their character may require. Said pins are shown projecting from a block 36 located 55 within a recess 37 in feeder 34. At 38 is a plate shown secured by screws to block 36, a screw 39 extending from said plate and secured thereto (Fig. 8). Said screw extends freely through partition 34^a of the 60 feeder (Fig. 8), and at 40, 41 are nuts upon

said screw respectively received in the recesses 37 and 42 of feeder 34, whereby, by adjusting said nuts, the screw may be advanced or retracted to correspondingly advance or retract pins 35 with respect to 70 feeder 34 and by setting the nuts tight against the partition 34^a said pins will be retained in set position projecting to the desired extent from the feeder. The forward edge of the bottom of magazine 26 is 75 shown recessed at 26^a opposite feeder 34 (Figs. 5 and 10) whereby the end portions of the label rest upon the projecting portions 26^b of the bottom of the magazine, and the lowermost label will extend over or 80 straddle at its mid portion the recessed portion 26^a (Figs. 5 and 10), whereby when the pins 35 engage said label the pins may pass through the recessed portion 26^a and carry the label along, causing its end portions to 85 be dragged from the projecting portions 26^b. By such means a label may be fed from the magazine each time that feeder 34 makes a rotation. At 43 is a guiding plate shown secured to the bottom of the magazine and curved to extend under feeder 34 in spaced relation thereto, to guide the labels that are carried along with the feeder by pins 35 (Figs. 3 and 6). Adjacent to the delivery end of guide plate 43 is a roller 90 34^b shown journaled upon a rock arm 34^c that is pivotally supported at 34^d on uprights 12, a spring 34^e coöperative with said arm and upright serving to resiliently press roller 34^b against feeder 34. At 44 are 100 spaced guides or ways shown in channel form, with the channel portions facing one another (Figs. 5 and 18), the inner ends of said guides being adjacent to the delivery edge of guide plate 43 and roller 34^b whereby labels will be delivered by feeder 34 and its pins from said guide plate into the channels of guides 44. At 45 are stops carried by the guides 44 (Figs. 1, 3 and 18), against which the labels 3 are stopped to bring said 110 labels to rest in proper position successively over the packages 2 on the conveyer in position to be applied to the packages. When feeder 34 rotates and its pins 35 engage a label, the latter will be drawn along by the 115 pins between the feeder and guide plate 43 and will be delivered with sufficient impetus into guides 44 to slide along the latter to be arrested by the stops 45.

Since it may be desirable to organize the 120 machine in such manner that labels of different sizes may be placed upon different sized packages, and also since labels of different thickness may be utilized in the same machine, I provide the following arrangement: To accommodate labels of different length or width in the magazine 26 the side walls 33 thereof are adjustable, for which purpose I have shown said walls carried by suitably shaped arms 46 shown re- 130

cessed at 46^a to receive the bottom of the magazine and shown having hubs 47 mounted adjustably upon rod 28 that is secured upon uprights 12 (Figs. 3, 6 and 9), set 5 screws at 48 serving to secure arms 46 of rod 28 in set position. The post 29 (Figs. 5, 6 and 9) is shown provided with a pair of adjustable guiding arms 49, which are shown slotted to receive screw 50 threaded into said 10 post, whereby said arms may be secured in adjusted position. By such means said arms may be adjusted with respect to the spaced position of side walls 33 of the magazine, according to the adjustment of the latter, 15 for guiding the slide 28 between such walls. The guides 44 are made adjustable to properly receive such labels therebetween. I have shown the guides as provided at their outer ends with slit portions 44^a and holes to receive a supporting rod 44^b, screws 44^c operating in the split portions serving to clamp the respective guides in set laterally adjusted position along said rod. The rod 44^b is shown carried by an arm 44^d having its 20 upper end split at 44^e and receiving screw 44^f for clamping the arm upon a bar 44^g that projects from bearing 72. Thus the guides 44 may be adjusted laterally and longitudinally, as required, for different labels to be 25 used. The guide rails 4^b are shown mounted for lateral adjustment to accommodate packages of different widths, for which purpose said rails are shown provided with laterally disposed slotted projections 4^e adapted to be 30 retained in set position by means of screws 4^d threaded in apertures in supports 9, 10, whereby said rails may be readily adjusted to properly guide and permit free travel of the packages 2 therebetween. The labels may 35 vary in thickness according to the requirements, and since all of the labels of the stack should preferably be supported at their bottom edges except the endmost label for delivery, I provide an adjustable bottom member 26^c for the magazine, which is shown located between spaced guide strips 26^d at said bottom, the latter being shown provided with a longitudinal slot 26^e (Figs. 9, 10 and 11), through which a screw 51^a projects from 40 bottom member 26^c, whereby a nut 51 on said screw coating with the bottom plates of the magazine may retain said bottom member 26^c in set position. By the arrangement described the bottom member 26^c may be projected more or less forwardly with respect to the recessed edge 26^a of the bottom of the magazine, whereby the proper space between the bottom portion 26^c and feeder 34 may be provided to permit the sweeping of the labels 45 successively from the stack by pins 35 of feeder 34. The periphery of roller 34^b is grooved for the free passage of pins 35 (Figs. 6 and 7).

When the labels have been deposited successively in guides 44 the labels are to be

pushed from the guides upon the packages, and before the labels are applied upon the packages suitable adhesive material or paste is to be applied either upon the package or upon the corresponding label, or both. In 70 the example illustrated in the accompanying drawings means are provided for applying adhesive material or paste upon the package before the latter is carried under the label. I have shown a paste pot or receptacle 52 75 carried by an arm 53 secured upon a shaft 54 journaled in uprights 12, and at the free end of said paste pot rolls 55 are journaled in position over a package 2 on conveyer 4 when the latter is brought to rest. A bearing 56 projecting from the paste pot supports shaft 57 that carries said rolls, and the rolls extend into the paste pot through slots 52^a in the wall of the latter (Figs. 12 and 13) to dip into the paste or adhesive 80 material in pot 52. A plate 58 may be secured in the pot and be provided with slots 52^a closely adhering to the rolls 55 to prevent the escape of paste from the pot (Figs. 12 and 14), serving also to scrape 85 paste from said rolls to prevent an excess thereon. I provide means to lower the paste pot with rolls 55 toward and to raise the same from packages 2, and to cause rotation of said rolls coincidently with such operation of the paste pot. I have shown a ratchet wheel 59 secured upon shaft 57 and adapted to coöperate with oppositely disposed spring-pressed pawls 60 and 61, which pawls are pivotally supported by an arm 62 90 that is journaled upon shaft 11 between collars 63 secured thereon to prevent lateral play of said arm (Figs. 1, 2, 13, 16 and 17). Arm 62 is shown provided with a link 64 that is pivotally connected with said arm 100 and with shaft 57, the pawl 61 being pivotally carried by said link, whereby the relation of the pawls and arm 62 to shaft 57 and ratchet 59 is maintained. Pawl 60 is shown pivotally carried by a projection 65 105 extending from arm 62. Shaft 54 may be rocked by any suitable means. I have shown said shaft provided with a crank arm 66 the free end of which is pivotally connected with an arm 67 (Fig. 3) shown 110 having a strap or cap 68 receiving an eccentric or cam 69 secured on shaft 11, whereby as shaft 11 is rotated the shaft 54 will be rocked to cause corresponding rocking of the paste pot. When the paste pot moves downwardly toward the package 2 on conveyer 4 the pawl 60, through ratchet 59, will cause rotation of rolls 55, and when the paste pot and rolls about reach the limit of the downward stroke said rolls will engage the package 2 therebeneath and apply paste thereon. When the paste pot next rises from the package 120 the pawl 60 will slip on the ratchet and pawl 61 on the ratchet will cause further rotation of rolls 59. Each time the 125

paste pot is lowered the rolls apply paste to a succeeding package, as indicated at 2^a in Fig. 1. While I have shown two rolls 55 in conjunction with the paste pot, whereby 5 two daubs of paste are applied upon a package, it will be understood that one or more rolls may be used if desired for the purpose.

After the paste or adhesive material has been applied upon a package, the latter is 10 brought to rest beneath a label, then in position upon guides 44, whereupon the label is advanced to the package and pressed upon the paste thereon. To accomplish such purpose I have shown a foot or presser 70 carried 15 by a reciprocative rod or plunger 71, shown slidable in a guide or bearing 72 carried by an arm 73 shown projecting from the uprights 12 (Figs. 1, 2 and 3). A spring 74, shown coiled upon rod 71 and pressing at 20 one end against guide 72 and at the other end against a head 71^a on said rod, serves normally to raise the rod and presser. At 75 is a rocking arm shown pivotally connected by a pin and slot connection at 76, 77 with 25 rod 71, said rocking arm being shown pivotally supported upon rod 78 carried by uprights 12, the collars 79 on said rod limiting lateral movement of arm 75 thereon. A reciprocating rod 80 is shown pivotally connected at 81 with arm 75, which rod is shown 30 forked at 80^a to receive and be guided on shaft 11 (Fig. 4). An eccentric or cam 82 upon said shaft is coöperative with said rod through the medium of a projection or roller 83 on said rod, whereby when shaft 11 is rotated the arm 75 will be rocked to cause 35 reciprocation of rod 71 and foot or presser 70 in timed relation to the stopping of packages 2 beneath said presser and the delivery 40 of a label therebetween.

The operation of my improvements may be described as follows: A supply of labels having been placed in the magazine 26 and a supply of adhesive material or paste in the 45 paste pot 52, and the machine being started, conveyer 4 will operate step by step and the presser and paste pot will reciprocate. The packages 2 will be successively placed upon the conveyer in spaced relation thereon, and 50 each time that shaft 11 makes a rotation the label feeder 34 through the medium of its pins 35 will have fed a label from the stack into the guides 44 against the stops 45, while the foot or presser 70 is elevated. Each time 55 the conveyer comes to rest (or, if preferred, during the progress of the conveyer), when a package is beneath the paste pot the latter will descend to cause its rolls 55 to bear upon such package to apply paste thereto, where- 60 upon when such pasted package comes to rest beneath presser 70 and a label thereon, the cam or eccentric 82 will cause depression of rod 71 and presser 70, whereupon the latter will push a label then in guides 44 from 65 the latter down upon the paste on the pack-

age for adhesion thereto. When the presser next rises the conveyer is moved a step to bring another pasted package beneath the presser, during which time and while the presser is above guides 44 feeder 34 will feed 70 another label to the guides ready to be pushed by the presser upon such pasted package, and so on for each package. It thus will be understood that the feeding of 75 the packages, the application of paste there- 80 to, and the applying of the labels upon the pasted packages will proceed successively in proper order for each package to be labeled. The labeled packages may be removed from the conveyer manually or may be delivered 85 to any desired means for receiving and removing the same.

Having now described my invention what I claim is:—

1. A labeling machine comprising a conveyer for packages, means to operate the conveyer, a magazine for a stack of labels, spaced guides, means to move the labels from the magazine to a position between the guides opposing the packages successively, 90 means to apply paste between the packages and labels successively, and means to pass between the guides to successively deposit the positioned labels from the guides upon packages. 95

2. A labeling machine comprising means to support packages, a magazine for labels, spaced guides for the labels opposing the packages, means to deliver labels from the magazine between the guides successively, 100 means to apply paste between the packages and labels, and means movable between the guides to move the labels from the guides and deposit the labels upon the adhesive on the packages. 105

3. A labeling machine comprising means to support packages, a magazine for labels, spaced guides for the labels opposing the packages, a feeder having means to remove the labels successively from the magazine and enter them in said guides for supporting the labels between the guides over the packages, means to operate the feeder, means to apply adhesive between the packages and labels, and means to move the labels from 110 between the guides and deposit the labels upon the adhesive on the packages. 115

4. A labeling machine comprising means to support packages, a magazine for labels, spaced guides for the labels opposing the packages, a feeder having pins to remove the labels from the magazine, means to operate the feeder, means to guide the labels to position between the first named guides, means to apply adhesive material between the packages and labels, and means movable 120 between said guides to move the labels from the guides and deposit the labels upon the adhesive upon the packages. 125

5. A labeling machine comprising means 130

to support packages, a magazine for labels, spaced guides for the labels opposing the packages, a feeder having pins to remove the labels from the magazine, means to operate the feeder, means to guide the labels to position between the first named guides comprising a guiding plate adjacent to the feeder and terminating adjacent to the receiving ends of said guides, and a roller co-operative with the feeder adjacent to said spaced guides, said roller having grooves to permit the passage of the pins, and means to move the labels from the guides and deposit the labels upon the adhesive on the packages.

6. A labeling machine comprising means to support packages, a magazine for labels, guides for the labels opposing the packages, a feeder having pins to remove the labels from the magazine, means to operate the feeder, means to guide the labels to the first named guides comprising a guiding plate adjacent to the feeder, and a roller co-operative with the feeder, said roller having grooves to permit the passage of the pins, a spring-operative arm carrying said roller in resilient contact with the feeder, and means to move labels from the guides and deposit the labels upon adhesive on the packages.

7. A labeling machine comprising means to support packages, a magazine for labels, spaced guides to receive labels opposing the packages, a feeder having means to feed labels from the magazine to said guides, means to operate the feeder, means to apply adhesive material between the packages and labels, a presser opposing the packages, a rod carrying the presser, a guide for the rod, an arm operatively connected with the rod, and means to rock said arm to reciprocate the rod and presser, to cause the presser to pass between said guides to remove the

labels from the guides and deposit them upon the packages.

8. A labeling machine comprising a conveyer for packages, means to operate the conveyer step by step, a paste pot located over the conveyer and provided with a roll to apply paste upon packages on the conveyer, means to rock the paste pot to present the roll to and remove it from the packages successively, a toothed wheel connected with the roll, a pawl to co-operate with the wheel, an arm supporting the pawl to cause rotation of the roll during movement of the paste pot, means to present labels over the pasted package, and means to apply the labels successively upon successively pasted packages.

9. A labeling machine comprising a conveyer for packages, means to operate the conveyer step by step, a paste pot located over the conveyer and provided with a roll to apply paste upon packages on the conveyer, means to rock the paste pot to present the roll to and remove it from the packages successively, a toothed wheel connected with the roll, pawls to co-operate with said wheel, an arm, a link movably connecting the arm to the shaft of the roll, one of said pawls being carried by said link and the other pawl carried by said arm, means supporting said arm whereby the roll will be rotated during rocking of the paste pot, means to present labels over the pasted packages, and means to apply labels successively upon successively pasted packages.

Signed at New York city in the county of New York and State of New York this 28th day of December A. D. 1917.

ERNEST D. ANDERSON.
